CLAIM

The ornamental design for a head wound dressing as shown and described.

DESCRIPTION

FIG. 1 is a perspective view of a head wound dressing showing my new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The broken lines in the figures are included for the purpose of illustrating unclaimed environment and form no part of the claimed design.
